UNITED STATES PATENT OFFICE.

ISIDORE SILVERBERG, OF FAR ROCKAWAY, NEW YORK, ASSIGNOR TO SILVERBERG IMPORT COMPANY, INCORPORATED, A CORPORATION OF NEW YORK.

VEIL.

1,293,221.

Specification of Letters Patent.

Patented Feb. 4, 1919.

Application filed April 20, 1918. Serial No. 229,784.

To all whom it may concern:

Be it known that I, ISIDORE SILVERBERG, a citizen of the United States of America, and resident of Far Rockaway, in the county of 5 Queens and State of New York, have invented certain new and useful Improvements in Veils, of which the following is a specification.

My invention relates to a veil adapted to 10 be used by women to cover the face, or face and front hair, or face and hat, as the purpose of use may require.

I have illustrated my invention in the accompanying drawings designating the parts 15 by letters and referring to like parts by like letters.

Figures 1 and 2 are both perspective views, the first illustrating the manner in 20 which the veil is applied and the second showing the veil applied and covering the face and hat of the wearer.

a indicates the veil which is preferably of 25 open work textile fabric, with a large mesh and woven of delicate fibers, but of course it may be of any suitable material. *b* is an elastic cord of rubber or other elastic material secured to the edge of the veiling, said 30 cord being circuitous. A convenient way of attaching the cord to the veiling is to weave the same into the adjacent meshes of the material along the edge thereof and secure the ends of the cord together, but of course the cord may be woven into the fabric or otherwise secured thereto.

The veil is generally applied by placing 35 one edge thereof under the chin as illustrated in Fig. 1 and with the hands distending the same to embrace the upper part of the head or head and hat as the case may be, 40 and withdrawing the hands, thus leaving the veil in place as a face covering as well as serving the purpose of holding the hair

or hat, or both, in place against disturbance by the wind or otherwise.

I am aware that hair nets of textile material and provided with a circuitous elastic cord substantially like the veil described by me have been used to confine the hair at the back of the head or on the top thereof, but I believe that I am the first to suggest the use 45 of such nets as a veil is used over the face and head in position beneath the chin, and over the front part of the head or hat as the case may be for the dual purpose of protecting or ornamenting the face of the wearer, 50 or for any other purpose for which a veil may be worn and at the same time confining the front hair and holding the hat or other head covering in position.

I therefore do not claim such netting with 55 elastic confinement broadly for any purpose, but I have limited my claim to the use of said article as a veil and for the specific purpose and uses stated, that is to say, as a veil 60 with the dual purpose of covering the face, 65 or face and head covering, and securing the same under the chin of the wearer and over the head or head covering as the case may require.

What I claim is:

A veil for the purposes described comprising a piece of open mesh fabric of a size to cover the face and head of the wearer, provided around its entire outer edge with an elastic cord secured thereto whereby said 75 veil is retained in proper position in use, solely by said elastic cord.

Signed by me at New York city, N. Y., this 19th day of April, 1918.

ISIDORE SILVERBERG.
